HOLDER FOR BOBBY PINS OR THE LIKE

Charles W. Ball, Bridgeport, Conn., assignor to
The Crown Plastics Corporation, Bridgeport,
Conn., a corporation of Connecticut

Application June 4, 1949, Serial No. 3,049

Term of patent 3½ years

(Cl. D86—10)

To all whom it may concern:

Be it known that I, Charles W. Ball, a citizen of the United States, residing at Bridgeport, county of Fairfield, and State of Connecticut, have invented a new, original, and ornamental Design for a Holder for Bobby Pins or the like, of which the following is a specification, reference being had to the accompanying drawing, forming part thereof.

Figure 1 is a plan view of a holder for bobby pins or the like, showing my new design; and Fig. 2 is a side elevation thereof.

I claim:

The ornamental design for a holder for bobby pins or the like, as shown,

CHARLES W. BALL.
